(109 Bergen Turnpike, Little Ferry, N.J.)

Filed Jan. 31, 1964, Ser. No. 78,449

Term of patent 14 years

(Cl. D13—7)

FIGURE 1 is a perspective view of my novel design for a combined post, hand railing and bracket or similar article shown with the center portion of both the post and the railing broken away for convenience in illustration only;

FIGURE 2 is an end elevation thereof shown with the center portion of the post being broken away for convenience in illustration only;

FIGURE 3 is a top plan view of the design shown with the ends of the railing being fragmentary and broken away for convenience in illustration only; and

FIGURE 4 is a rear elevational view of the post shown in FIGURES 1, 2 and 3, shown with one end of the post being fragmentary and broken away for convenience in illustration only.

I claim:

The ornamental design for a combined post, hand railing and bracket or similar article, substantially as shown and described.
